UNITED STATES PATENT OFFICE.

JAMES H. NORTHRUP, OF HOPEDALE, MASSACHUSETTS, ASSIGNOR TO THE DRAPER COMPANY, OF SAME PLACE AND PORTLAND, MAINE.

BRAKE MECHANISM FOR LOOMS.

SPECIFICATION forming part of Letters Patent No. 593,070, dated November 2, 1897.

Application filed May 22, 1897. Serial No. 637,669. (No model.)

To all whom it may concern:

Be it known that I, JAMES H. NORTHRUP, of Hopedale, in the county of Worcester and State of Massachusetts, have invented an Improvement in Brake Mechanism for Looms, of which the following description, in connection with the accompanying drawings, is a specification, like letters on the drawings representing like parts.

10 This invention relates to brake mechanism for looms whereby the brake is automatically applied when the shipper is knocked off to stop the loom and automatically released when the shipper is again moved to start the loom.

15 The construction hereinafter to be described is such that the brake can be manually released while the loom is stopped in order that it may be moved by hand by the attendant, as is often necessary.

20 The manual controlling member by which release of the brake is effected during stoppage of the loom is attached to the shipper-lever and is so constructed that movement of the shipper into running position will throw 25 it out of operation automatically, as will be fully described.

Figure 1, in elevation, represents a sufficient portion of a loom side to be understood with my present invention applied thereto, the 30 parts being shown in the position assumed when the loom is running. Fig. 2 is a partial front elevation of the apparatus shown in Fig. 1. Fig. 3 is a like view, the parts being shown in position to apply the brake and stop the 35 loom. Fig. 4 is an enlarged view in elevation of the manual controlling member detached. Fig. 5 is an enlarged detail of some of the parts, the controlling member being shown in operative position to release the brake; 40 and Fig. 6 represents side and end elevations of the supporting-stand for the controlling member.

The loom side A, breast-beam B, having the usual notched holding-plate B' for the shipper-lever B^X, the fast and loose pulleys C and C', the brake-wheel C^X, secured to or to rotate with the fast pulley, the belt-shipper B², and connections between it and the shipper-lever are and may be of usual construction 45 and need not be described in detail herein.

I have herein shown the brake-shoe D as a suitably-shaped arm pivoted at D' to the loom side (see Fig. 1) and jointed at d' to a rod d, slotted at its forward end to receive a stud d² on the usual frog F, the latter when operated 55 by a dagger, (not shown,) upon absence of the shuttle, acting through a suitable elbow-lever d^X to knock off the shipper-lever B^X, all as common in looms, the operation of the frog applying the brake through the rod d. 60

A collar d³ on the brake-rod (see Fig. 1) is adapted to be engaged by the upturned short arm a' of a lever a, pivotally mounted at a² on a stud secured to the loom side, the lever a supporting a weight W, the hooked stem w 65 thereof being adapted to engage one of a series of notches a^X in the lever-arm a to adjust the weight toward or from the fulcrum a². The weight when free to act moves the lever a' into dotted-line position, Fig. 1, and 70 through the rod d applies the brake, the lever and weight constituting a brake-actuator.

A bracket or stand b, having an extended toe b' and an outwardly-bent upturned ear b², is rigidly secured to the side of the shipper-lever B^X adjacent its fulcrum b^X, the toe b' being of sufficient length to extend beneath the lever-arm a, maintaining it raised in full-line position, Fig. 1, and as shown in Fig. 2, when the shipper-lever is in running position, 80 with the brake released.

When the shipper-lever is moved to stopping position, Fig. 3, the toe b' is lowered to release the brake-actuator, thereby permitting the latter, acting by virtue of the weight 85 W, to apply the brake automatically, whether the movement of the shipper-lever is effected automatically or by hand.

It is very desirable that the brake may be released while the loom is stopped in order 90 that the attendant may move the operative parts of the loom by hand, and for this purpose I provide a manually-operated controlling member, whereby the brake may be released at such time.

The controlling member is shown separately in Fig. 4 as a disk-like hub c, having a cam c' on its periphery and a non-radial arm c², secured to or forming a part of the cam, the outer end of the arm being enlarged to in- 95 100

crease the weight, as at c^3 , and serve as a handle. The hub is mounted to rock freely on the shipper-lever fulcrum b^x between the said lever and the ear b^2 of the stand b , said ear having thereon a stop b^3 to coöperate with the face c^4 on the inner end of the arm c^2 , limiting its movement in one direction, as shown in Fig. 5. Movement of the controlling member in the other direction is limited by engagement of the face c^5 of the arm with the straight edge b^4 of the ear b^2 in Figs. 2 and 3. The lever-arm a has a laterally-extended finger a^5 , which projects above and in the plane of the hub c and its cam c' , and when the loom is running the toe b' holds up the arm a , the finger a^5 being out of engagement with the manual controlling member, as in Fig. 2. When the shipper is in stopping position, Fig. 3, however, the release of the brake-actuator by the toe b' permits the finger a^5 to rest upon the hub c , the normal position of the controlling member relative to the shipper-lever being shown in Figs. 2 and 3. If now it is desired to release the brake without starting the loom, the attendant grasps the handle c^3 of the controlling member and turns it up into position shown in Figs. 4 and 5, thereby bringing the cam c' up over or a little past the dead-center—viz., the fulcrum b^x —the cam acting on the finger a^5 and raising the lever-arm a to release the brake. The position of the cam above center and the pressure of the brake-actuator thereupon retains the controlling member in such position until the shipper-lever is returned to running position, whereupon the cam c' is withdrawn from the finger a^5 , the actuator is engaged and held inoperative by the toe b' , and the controlling member returns by gravity to normal position.

A suitable spring S , attached at one end to the loom-frame and at the other end to the shipper-lever, acts to throw the latter when released from its holding-notch.

The slot-and-stud connection between the brake-rod d and the frog F permits the brake-actuator to apply the brake when the shipper-lever is knocked off by reason of failure of the filling or by hand without operating the frog.

The stop b^3 limits the movement of the manual controlling member when operated to release the brake while the loom is stopped.

The mechanism herein shown is simple, strong, readily operated, and not liable to break or get out of order.

It will be, of course, obvious that the shipper-lever may be moved directly to running position from the position shown in Fig. 3 without any intervening operating of the manual controlling member.

Having fully described my invention, what

I claim, and desire to secure by Letters Patent, is—

1. In a loom, a brake, an actuator therefor, a shipper-lever coöperating with said actuator whereby stopping movement of the shipper-lever automatically releases the actuator to apply the brake, and a controlling member for said actuator, mounted on the shipper-lever, said controlling member being adapted to be moved by the operator independently of the shipper-lever, to release the brake while the loom is stopped, substantially as described. 75

2. In a loom, a brake, an actuator therefor, a shipper-lever coöperating with said actuator whereby stopping movement of the shipper-lever automatically releases the actuator to apply the brake, and a controlling member for the actuator, pivoted on the shipper-lever and adapted to be moved by the operator over its dead-center to release the brake while the loom is stopped, movement of the shipper-lever to running position disengaging the brake-actuator and controlling member, and permitting the latter to return to normal position, substantially as described. 85

3. In a loom, a brake, an actuator therefor, a shipper-lever coöperating with said actuator whereby stopping movement of the shipper-lever automatically releases the actuator to apply the brake, and a controlling member for the actuator, pivotally mounted in alignment with the shipper-lever fulcrum, and adapted to be moved by the operator to release the brake while the loom is stopped, movement of the shipper-lever to running position releasing said controlling member and reengaging the brake-actuator, substantially as described. 90

4. In a loom, a brake, an actuator therefor, a shipper-lever having a projection to coöperate therewith, whereby stopping movement of the shipper-lever automatically releases the actuator to apply the brake, and a finger forming a part of the actuator, a hand-controller having a cam portion adapted to be moved by the operator to engage said finger, and thereby release the brake while the loom is stopped, movement of the shipper-lever to running position bringing the projection thereon into engagement with the brake-actuator, and disengaging the actuator-finger and the hand-controller, the latter returning to normal position by gravity, substantially as described. 105 110 115

In testimony whereof I have signed my name to this specification in the presence of two subscribing witnesses.

JAMES H. NORTHROP.
